UNITED STATES PATENT OFFICE.

PATRICK G. McKEON, HAROLD A. MOLES, AND JOHN J. VARNER, OF TULSA,
OKLAHOMA.

OIL-WELL PUMP.

Application filed February 28, 1925. Serial No. 12,417.

To all whom it may concern:

Be it known that we, PATRICK G. McKEON, HAROLD A. MOLES, and JOHN J. VARNER, citizens of the United States, residing at 5 Tulsa, in the county of Tulsa and State of Oklahoma, have invented certain new and useful Improvements in Oil-Well Pumps, of which the following is a specification.

The object of our invention is to provide 10 a novel oil-well pump, eliminating the use of the well known forms of cups and packing customarily employed, and thereby obviating the constant wearing thereof and the frequent pulling of the tubing and rods, 15 etc.

The invention resides, specifically, in a novel form of plunger depending from the traveling valve of the pump, and, while such plunger has been shown in the accompanying 20 drawing as associated with the traveling valve of an oil-well pump, it is to be understood that it is adapted for use, with equal efficiency and facility, in other situations.

25 We have shown in the drawing, which forms part of this specification, only so much and so many parts of an oil-well pump as are necessary for an understanding of the application of our invention. Briefly described:

Figure 1 is a vertical sectional view of a portion of the pump, certain parts being shown in elevation; and

Figure 2 is a fragmentary view, in elevation, of the traveling valve and associated plunger.

Referring, now, in detail to the drawing:

1 designates a portion of one section of the oil-well casing or lining, and 2 the 40 pump-barrel carrying, at its lower end, the stand-valve designated generally by the reference-numeral 3.

4 designates the valve-stem carrying the traveling valve designated generally by the 45 reference numeral 5. Screwed into the lower end of the valve 5 is the hollow plunger-rod 6, a jam-nut 7 being screwed on the upper end thereof and against the lower end of the valve 5.

50 Encircling the plunger-rod 6 are washers

8 and 9, of the same diameter as the bore of the pump-barrel 2. The washer 9 rests upon a nut 10 screwed on the lower end of the plunger-rod.

Encircling the plunger-rod 6 is a coiled 55 spring 11, one end thereof bearing against the nut 7 and its other end against the washer 8.

Interposed between the washers 8 and 9 are spherical members 12, of any size, kind 60 or substance, such as chilled shot, or steel balls, of any suitable diameter, but preferably small, and of a number sufficient to compactly fill the space between the collars 8 and 9 and between the pump-barrel 2 and 65 the plunger-rod 6. The spherical members make an infinite number of perfect contacts with the pump-barrel 2, and make it possible to dispense with the customary cup-pistons and packings used in oil-well pumps. The 70 spherical members, used as packings, have the advantages over the customary forms of cups and packings, because they are far more durable and efficient.

Having thus fully described our invention, what we claim as new and desire to secure by Letters-Patent of the United States is:

1. In a piston for use in a cylindrical casing comprising a piston-rod, spaced washers on said rod and spherical metallic bodies retained between said washers to substantially fill the space between the casing and the piston-rod.

2. In a piston for use in a cylindrical casing comprising a piston-rod, spaced washers on said rod, substantially non-deformable spherical bodies disposed between said washers and filling the space between the casing and piston-rod and a coiled spring 80 encircling said piston-rod and bearing on one of the washers to exert a yielding pressure effective to retain the spherical bodies in compact form and in close contact with the casing.

In testimony whereof, we hereunto affix our signatures.

PATRICK G. McKEON.
HAROLD A. MOLES.
JOHN J. VARNER.
